US0D1096455S

(12) **United States Design Patent** (10) Patent No.: **US D1,096,455 S**
(45) Date of Patent: ** Oct. 7, 2025

(54) **IRRIGATION CONTROLLER**

(71) Applicant: **Bermad CS LTD.**, Kibbutz Evron (IL)

(72) Inventors: **Shay Shtekelmacher**, D.N. Galil Elion (IL); **Ilan Shklarsh**, Kibbutz Daliya (IL); **Shay Chamoy**, Ramat Yishai (IL); **Amit Shtutman**, Rakefet (IL)

(73) Assignee: **BERMAD CS LTD.**, Kibbutz Evron (IL)

(**) Term: **15 Years**

(21) Appl. No.: **35/522,696**

(22) Filed: **Sep. 29, 2024**

(80) **Hague Agreement Data**

Int. Filing Date: **Sep. 29, 2024**

Int. Reg. No.: **DM/240893**

Int. Reg. Date: **Sep. 29, 2024**

Int. Reg. Pub. Date: **Oct. 18, 2024**

(30) **Foreign Application Priority Data**

Jul. 18, 2024 (IL) 72826

(57) **CLAIM**

The ornamental design for an irrigation controller as shown and described.

DESCRIPTION

1. Irrigation controller

1.1 : Perspective

1.2 : Perspective

1.3 : Front

1.4 : Left

1.5 : Right

1.6 : Top

1.7 : Bottom

1.8 : Back

The product incorporating the design is used as an irrigation controller; the essential features of the design lie in its shape; the perspective view in figure 1.1 is designated to best show the essential features of the design; the broken lines in the drawings illustrate portions of the irrigation controller that form no part of the claimed design.

1 Claim, 8 Drawing Sheets
